GARDEN CENTER BUILDING

Frank T. McCoy, Jr., Nashville, Tenn., assignor, by mesne assignments, to Garden Centers, Inc., Nashville, Tenn., a corporation of Tennessee

Filed July 18, 1960, Ser. No. 61,404

Term of patent 14 years

(Cl. D13—1)

FIGURE 1 is a front elevational view of a garden center building disclosing my design;

FIGURE 2 is a rear elevational view of the building of FIGURE 1;

FIGURE 3 is a left side elevational view of the building of FIGURE 1; and

FIGURE 4 is a right side elevational view of the building of FIGURE 1.

FIGURE 5 is a fragmentary cross-sectional view taken on line 5—5 of FIGURE 2.

The figures of the drawing are shaded, except for the surface shading on the window and door glass of FIGURES 1 and 3 and the fiber glass roof skylight panels of FIGURES 3 and 4, to indicate the distinctive color scheme adopted for the building, characterized by the inset front, the front panel divider stripping and bounding border-like beams enclosing the floor level solid panels,

the shoulder height transparent glass panels and the triangularly arranged louvre structure crowning the single row of solid panelling immediately above the glass panels and corner door structure as best seen in FIGURE 1.

I claim:

The ornamental design for a garden center building, as shown and described.
